P. BAHR.
LIFE PRESERVER.
APPLICATION FILED AUG. 3, 1914.

Patented Feb. 9, 1915.

UNITED STATES PATENT OFFICE.

PAUL BAHR, OF CHICAGO, ILLINOIS.

LIFE-PRESERVER.

1,127,848.

Specification of Letters Patent.

Patented Feb. 9, 1915.

Application filed August 3, 1914. Serial No. 854,633.

To all whom it may concern:

Be it known that I, PAUL BAHR, a subject of the Emperor of Germany, residing at Chicago, in the county of Cook and State of Illinois, have invented certain new and useful Improvements in Life-Preservers, of which the following is a specification.

This invention relates to life preservers generally in the form of a satchel or valise which when empty may be hermetically sealed and attached to the body of the wearer.

With the above and other objects in view this invention consists in the construction, combination, and arrangement of parts all as hereinafter more fully described, claimed, and illustrated in the accompanying drawing wherein:

Figure 1 is a view illustrating the present invention attached to a wearer; Fig. 2 is an elevation of the grip opened to illustrate the arrangements of the parts; Fig. 3 is a central vertical section through the grip; Fig. 4 is a section along line 4—4, Fig. 3, and illustrates the valve mechanism; and Fig. 5 is a similar view along line 5—5, Fig. 3, illustrating the mounting of the pump handle.

Reference being had more particularly to the drawings, 10 indicates a valise or grip in general, comprising the body 10^a and top 10^b, both being constructed of metal and binged together at 11. Snap locks 12 are provided about the free edges of the top 10^b and body 10^a whereby these elements may be securely locked together throughout their entire free length. Both the body 10^a and the cover 10^b are covered with leather or some other material recognized as proper in the manufacture of luggage, in order that the metallic nature thereof may be thoroughly disguised.

Each section 10^a and 10^b at their abutting edges, is provided with a semi-circular channelled rim 13. These rims abut when the valise or grip is closed and thus form a circular hollow tube at the joint between the sections 10^a and 10^b, which tube constitutes a seal for the joint between said sections as will be apparent. A continuous flexible rubber tube 14 is carried by the semi-circular rim of the body 10^a and upon closing the grip or valise 10 enters and completely fills the opposite rim 10^b of the cover. This tube when inflated completely fills the tube formed by the abutting rims 10^a and 10^b and

thoroughly seals the joint between said section, thereby hermetically sealing the closed valise or grip 10. It is, therefore, necessary to inflate the tube 14 and in order to accomplish this a pump cylinder 15 is mounted in the body 10^a and projects a short distance therefrom, terminating in an externally threaded hollow cup 16 (Fig. 5). A cap 17 is arranged to be threaded onto this cup and hermetically seals the same. Mounted for reciprocation in the pump cylinder 15 is a piston rod 18 carrying a piston or plunger 19 at one end, and projecting into the cup 16 at its other end where it terminates in a handle 20.

The lower end of the pump cylinder 15 communicates with a tube 21, which extends to a position adjacent to the tube 14. A valve casing 22 connects with both of the tubes 14 and 21 and constitutes an air inlet for the tube 14 from the pump. This valve casing 22 is centrally enlarged as at 22^a (Fig. 4) and has a valve stem 23 mounted in such enlargement through the medium of the cage 24. A spring 26 encircles the stem 23 and operates between a valve 25 and the cage 24 normally to force the valve into its seat to close the inlet from the tube or pipe 21. An exhaust pipe 27 is secured to the enlargement 22^a of the valve casing 22 at a point where the air in the tube 14 will enter the same. This exhaust pipe pierces the end of the grip 10 where it is provided with a cap 28.

In use the grip is emptied and locked closed, the cap 17 removed from the cylinder 15, and the pump operated. This operation forces air through the tube 21 against the valve 25, moving the same on its stem 23 against the action of the spring 26. The air thus enters the valve casing and passes through the cage 24 into the tube 14. The tube 14 being inflated hermetically seals the grip 10, and transforms it into a life preserver. As soon as the pumping action stops, the spring 26 seats the valve 25 and closes the inlet.

To attach the device a body belt 29 of fabric is provided which encircles the body 10^a and which when not in use is rolled and held by the strap 30 that surrounds the grip as in Fig. 3. When the device is in use the straps 30 are loosened to pass over the shoulders of the wearer to support the grip 10. Should the grip 10 be opened while the tube 14 was inflated the removal of the em-

bracing rims thereby might cause the tube 14 to burst under the pressure of the air. To obviate this the exhaust pipe 27 and its cap 28 is provided. The removal of the cap 28 permits the air in the tube 14 to escape through the pipe 27.

While the preferred form of this invention is shown and described, it will be understood that changes may be made in the 19 details of construction without departing from the spirit and scope thereof.

I claim as my invention:

1. The combination with a receptacle, comprising a body and a hinged cover 15 therefor, of a normally deflated pneumatic seal for the joint between said cover and body, a pump within said receptacle and operable from the exterior thereof, a connection between said pump and said seal, 20 and an exhaust coöperating with said seal and extending to the exterior of said receptacle.

2. The combination with a receptacle comprising a body and a cover hinged 25 thereto, of a normally deflated pneumatic seal for the joint between the body and the cover, a pump within said receptacle and operable from the exterior thereof, a valve casing connected with said seal, a one-way 30 valve within said casing, a connection between the valve casing and the pump whereby the operation of the latter will open said valve and inflate said seal, and an exhaust pipe communicating through the 35 valve casing, independently of the valve, with seal and controlled from the exterior of the receptacle.

3. The combination with a receptacle

comprising a body and a hinged cover, of a normally deflated pneumatic seal for the 40 joint between said cover and body, a pump within said receptacle, a valve casing connected with said seal having a valve seat and spring-actuated valve coöperating therewith, an exhaust connected with said 45 casing and projecting from the receptacle aforesaid, means for closing said exhaust, and a connection between said pump and said valve casing coöperating with said valve casing for inflating the seal aforesaid and opening the valve against the action of its spring.

4. The combination with a receptacle comprising a body and a hinged cover therefor, of a normally deflated seal for the 55 joint between said cover and body, a force pump located within said receptacle and operable from the exterior thereof, a valve casing connected with said seal at one terminal and with the pump at the opposite 60 terminal, a valve seat within said casing adjacent to the pump connection thereof, a spring for forcing said valve into said seat, and an exhaust pipe connected with the valve casing and projecting from the receptacle, said exhaust pipe connecting directly with the seal to the rear of the valve aforesaid and arranged to deflate said seal without movement on the part of the valve.

In testimony whereof I have hereunto 70 affixed my name in the presence of two witnesses.

PAUL BAHR.
